UNITED STATES PATENT OFFICE.

JOHN LUCAS, OF HASTINGS, MINNESOTA.

WHEAT, OAT, AND COCKLE SEPARATOR.

SPECIFICATION forming part of Letters Patent No. 322,548, dated July 21, 1885.

Application filed February 24, 1883. (No model.)

To all whom it may concern:

Be it known that I, JOHN LUCAS, a citizen of the United States, residing at Hastings, in the county of Dakota and State of Minnesota, 5 have invented a new and useful Wheat, Oat, and Cockle Separator, of which the following is a specification.

This invention relates to wheat, oat, and cockle separators; and it consists in the novel 10 construction and combination of parts, which will be first fully described, and then pointed out in the claims.

In the drawings, Figure 1 is a perspective, and Fig. 2 a vertical longitudinal section, of 15 my machine. Fig. 3 is a detail view of one of the slides. Fig. 4 is a detail view of the elevator. Fig. 5 is a detail view of the end spout. Fig. 6 is a detail view of the lower supplemental sieve. Fig. 7 is a detached sectional 20 view of the main sieve and the endless slotted apron. Fig. 8 is a detail perspective view of the hopper and main sieve. Fig. 9 is a detail view of the slide-sections. Fig. 10 is a detail view of the upper supplemental sieve. Fig. 25 Fig. 11 is a detail view of the side spout, all of which will be described.

The supporting-frame of my machine is formed of the inclined side boards, A A, supported by their upper forward ends by legs 30 B, which are slotted vertically at b, and secured to the side frames by set-screws b', passed through said slots, so the side boards can be adjusted vertically to vary their inclination. Legs C C support the lower end of the side 35 boards, and an end board, C', extends between and connects said legs C. The side boards are provided in their upper ends with bearing-slots D, and in their lower ends with slots D', and the main sieve E is secured between said 40 side boards, below the slots D D', and at an incline, as shown. The hopper F is arranged at the upper end of the machine and provided with an agitating-roller, f, having an end pulley, f', and with a discharge-opening, F'. A 45 tilting board, G, is pivoted at its forward edge in advance of the opening F', and extended under and beyond said opening, with its rear edge over the upper end of the main sieve, as shown. This board G is provided at 50 or near its tilting edge with a spring-arm, G', which extends alongside of the hopper and engages the teeth of a rack, F'', so that the tilting board may be held at any desired inclination for the purpose of regulating the out-

flow of the grain. The endless apron H is 55 provided with cross-slats H', and is supported on rollers I I'. The roller I has its trunnions supported in slots D, and provided on one end with a pulley, i, and on its other end with a hand-crank, i', and a pulley, i''. The 60 pulley i'' is geared by belt i''' with pulley f', and thus operates the agitator f, as will be understood. The roller I' has its trunnions projected through slots D' and journaled in plates J, which are adjustably secured to the 65 side boards, A, by set-screws J', passed through slots j, so that the apron may be tightened when desired. This belt is moved in the direction indicated by the arrow in Figs. 1 and 2, and feeds the grain down on the main sieve. 70 A sieve, K, is arranged below the upper end of the main sieve and extended slightly below the middle part of said main sieve, as shown. I preferably pivot this sieve midway its ends, so it may be adjusted to any desired angle, and 75 it may be held at the desired angle by fitting it to bind between the side boards, A, or by set-screws, or other similar expedients, as desired. I also prefer to form this sieve with two screens, one above the other, as shown 80 most clearly in Fig. 2. The spout L is arranged at the side of the machine, below the side boards, A, and slightly nearer the lower than the upper end of the machine. Inclined grooves M are formed in the inner sides of 85 the boards A A, between the spout and the sieves K, and extend downward below the rear side of the spout and upward to a point about midway the ends of the sieve K. A cut-off board, M, is supported and movable in 90 these grooves above the spout L, and between the latter and the sieve K. By adjusting this cut-off to the position shown in Fig. 3 it will cut off the grain screened by the lower half of sieve K from spout L, and deliver same in 95 to the end spout, presently described. By adjusting this cut-off M in its grooves, the grain screened by the lower part of sieve K may be delivered into either the side or end spout, as desired. The sieve K, I denominate, for 100 purposes of reference, the "upper supplemental" sieve, and the sieve N, the "lower supplemental" sieve. This latter sieve is arranged below the sieve K, and has its lower end projected slightly over the side spout and its upper end extended to a line below the forward end of sieve K. This sieve is also preferably pivoted midway its ends for purposes of ad-

justment, and may be held in any desired position in a manner similar to that described with reference to the sieve K. A narrow board, O, is arranged at an incline between the 5 side boards, A, and has its lower edge resting on the upper side of the end board, C'. Inclined grooves P' P are formed one above the other and above the board O, and support the sliding cut-offs P P. The upper groove, 10 P', is extended nearly to the lower end of the upper supplemental sieve, and either or both the cut-offs P may be adjusted in their grooves to throw the screenings from the lower part of the main sieve over the end board or into 15 the end spout. This end spout, Q, discharges through an opening, C', in end board, C', and thence through an opening, R', into the case of the elevator R. This elevator is arranged at the discharge end of the machine, and is 20 provided with an endless carrying-belt, R², supported on rollers R³ R³, the upper one of which is provided with a pulley geared by belt S with pulley i on roller I. The grain, tailings, &c., delivered through opening R' 25 is taken up by the elevator and deposited by spout R⁴ onto the apron, by which it is carried upward and redelivered onto the main sieve. The elevator may be supported at its lower end by a foot-board, T, which rests on the 30 floor and may be screwed to the end board, C'. This foot-board holds the elevator away from the end board, C', and its upper end is inclined so as to throw the débris, &c., delivered over the end of the machine to opposite sides. The 35 upper end of the elevator is braced by the stay-rods U U, as shown. The cut-offs P P and M, it will be understood, may be held at any point of adjustment by fitting them sufficiently tight in the grooves P' M' to hold 40 them from any movement except when positively actuated, as will be seen.

In operation motion is given by crank i', and the grain passes out of the hopper and is carried by apron H down over the sieve E. 45 The unhulled grain, débris, &c., which fails to pass through sieve E is deposited at the end of the machine onto the floor or ground, where it may be collected and disposed of as desirable. The grain passed through the upper part of sieve E passes onto sieve K, and is screened through the same or passes off its lower end onto cut-off M, and thence into the end spout. By adjusting the said cut-off downward the grain screened by the lower 50 part of the sieve K may be delivered into the end spout, or the said board M may be set farther downward in its grooves so it will catch but a small quantity of grain screened by sieve K, the major part falling onto sieve N, and 55 thence into the side spout, as will be seen. The grain passes down sieve N, by which any fine dust or dirt is separated from it, and into the side spout, out of which it flows in proper condition for bagging. The main sieve is 60 coarser than the upper supplemental sieve, and the latter is coarser than the lower supplemental sieve, so the screened matter is re-

duced in quantity as it flows through the machine. The matter which is thrown off from the sieve E is cast out of the machine, and the other matter, except that which has been properly separated, is redelivered into the main sieve, and again run through the machine. 70

In starting the machine the tilting board is 75 adjusted to permit a full feeding, and as the elevator begins to deliver the grain onto the apron the feed from the hopper is limited according to the quantity brought up by the elevator, in order that the quantity of stuff 80 running through the machine may not exceed its capacity.

The supplemental sieves may be adjusted on their pivots to various angles, according to the quantity of grain passing through the 85 machine.

Having thus described my invention, what I claim, and desire to secure by Letters Patent, is—

1. In a grain separator, the combination, 90 with the main sieve and an endless carrying-apron, of an elevator arranged at the rear or discharge end of the sieve and adapted to receive the discharge of the machine and elevate such discharge onto the endless belt and 95 operating mechanism, substantially as set forth.

2. The combination, in a grain-separator, of the stationary inclined sieve, the endless apron having cross-slats and moving down 100 on the said sieve close thereto, and an elevator arranged at the rear end of the machine and adapted to receive the mixed grain and tailings and elevate and deliver the same onto the lower end of the slatted apron, whereby 105 they are redelivered onto the inclined screen, substantially as set forth.

3. In a grain-separator, substantially as described and shown, the combination of the sieve E, the slatted apron, the hopper, the 110 elevator arranged at the end of the machine and adapted to receive the mixed grain and tailings screened by the lower part of the sieve E, and deliver the same onto the slatted apron, and means whereby the discharge 115 from the hopper may be regulated, substantially as described, and for the purposes specified.

4. In a grain-separator, the combination of the main sieve, the sieve K, the cut-offs P, 120 the cut-off M, and the side and end spouts, substantially as set forth.

5. The combination of the main sieve, the sieves K and N, the spouts L and Q, and the cut-offs M and P, substantially as set forth. 125

6. The combination, with the main sieve, of the cut-offs P P, arranged below the lower end of the main sieve and adjustable one upon the other, substantially as set forth.

In testimony whereof I affix my signature 130 in presence of two witnesses.

Witnesses: JOHN LUCAS.
